UNITED STATES PATENT OFFICE

148,736

DESIGN FOR A DISPLAY STAND

Albert M. Travis, Kansas City, Kans., assignor to
John C. Hockery, Kansas City, Mo., as trustee

Application September 3, 1946, Serial No. 133,029

Term of patent 14 years

(Cl. D80—9)

To all whom it may concern:

Be it known that I, Albert M. Travis, a citizen of the United States, residing at Kansas City, in the county of Wyandotte and State of Kansas, have invented a new, original, and ornamental Design for a Display Stand, of which the following is a specification, reference being had to the accompanying drawing, forming part thereof, in which

Fig. 1 is an elevational view showing the side of a stand embodying my new design,

Fig. 2 is an elevational view of the front of the stand,

Fig. 3 is a top plan view of the stand, and

Fig. 4 is an elevational view of the rear of the stand.

The dominant features of the design reside in the portions shown in full lines.

I claim:

The ornamental design for a display stand, substantially as shown and described.

ALBERT M. TRAVIS.
